UNITED STATES PATENT OFFICE.

CORNELIUS TENNEY, OF BROOKLYN, NEW YORK.

HANDSAW.

SPECIFICATION forming part of Letters Patent No. 291,424, dated January 1, 1884.

Application filed November 9, 1883. (No model.)

To all whom it may concern:

Be it known that I, CORNELIUS TENNEY, a citizen of the United States, residing at Brooklyn, in the county of Kings and State 5 of New York, have invented certain new and useful Improvements in Handsaws; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 In the manufacture of saw-handles, among the objects sought, one is to effect a rigid and strong connection between the handle and blade, to prevent the breaking of the handle or its becoming loose. This result has hereby 20 tofore been reached, among other ways, notably by permitting to remain on the rear end of the blade that portion thereof which was unsuitable to form a part of the blade proper, and which was usually cut off, and by cutting 25 a hole in said portion or extension corresponding to the size and character of the hole in the handle which receives the hand, said handle being slitted almost its entire length to receive or admit the said extension sufficiently far into 30 it to bring the opening therein into coincidence with the hole in the handle, after which, of course, the latter was riveted to the blade in the ordinary manner. The objections to this method of bracing the handle are the additional trouble and time required to make 35 the opening in the blade and the extra depth of slit in the handle, and the securing of the end of the blade in rear of the hand-hole into the handle. Another difficulty arising from 40 this method of bracing the handle is the liability of the metal edges of the opening of the blade extension to protrude around the edges of the coincident opening of the handle, which may arise under various circumstances, and 45 injure the hand or render the hand uncomfortable.

To obviate these inconveniences and drawbacks is the object of my invention; and it therefore consists of a brace of the construc-

tion hereinafter described and claimed, where- 50 by a handle, either of ordinary construction or which may be of reduced size and connected to the blade in the ordinary way, can be firmly and strongly braced at its point of connection to the blade.

55 In the accompanying drawings, Figure 1 is a side view of a saw-handle and a portion of the blade, all of the usual construction, with my improvement applied thereto; and Fig. 2 is a rear elevation of the brace.

60 In carrying out this invention the rear end or edge of the blade A, at its lower corner, may be extended somewhat rearwardly, as at a, after which the handle B, which may be of either ordinary construction, or which may be 65 reduced to a minimum size, as shown, is then provided with a shallow slit extending only to the dotted lines a' of Fig. 1. This permits of the making of a very light handle, and consequently one only requiring a minimum 70 amount of material for its manufacture.

75 C is a brace, made of strong metal, one end of which is formed with an eye, c, adapted to fit against the under side of the handle B, near the lower horn thereof, and to which it is secured by a screw or other suitable fastening. From the eye c, the remaining portion of the brace, in its relative position to the handle, extends obliquely downward and forward, and embraces the lower rear edge, a, of the blade, 80 said brace being provided with a slot, c', to receive the said edge, to which it is secured by a rivet, d, passed through the brace and saw-blade. This arrangement effects a firm and strong connection between the blade and handle, (secured to the latter in the ordinary manner, as shown,) strengthens the blade, and reinforces the weak portion of the handle, preventing the liability of its breaking at that point, while it obviates the elongation of the 85 rear end of the blade and the extraordinary length of slit or slot heretofore made in the handle to receive the blade, said slot or slit almost severing the handle in two.

90 I am aware that it is not broadly new in 95 handsaws to secure to the lower edge of a handle a brace having a groove to receive the tail of the blade, the inner ends of the arms of the

brace having a bridge which rests upon the edge of the blade.

Having thus fully described my invention, what I claim, and desire to secure by Letters 5 Patent, is—

In a handsaw, the combination of a blade and handle, constructed substantially as shown and described, with a brace secured to the handle about opposite the hand-opening, and

having forwardly-projecting slotted arms firmly riveted or bolted to the blade, as and for the purpose set forth.

In testimony whereof I affix my signature in presence of two witnesses.

CORNELIUS TENNEY.
